US0D1099706S

(12) **United States Design Patent** (10) **Patent No.:** **US D1,099,706 S**
(45) **Date of Patent:** **** Oct. 28, 2025**

(54) **CONTAINER FOR PACKAGING**

(71) Applicant: **YONWOO CO., LTD.**, Incheon (KR)

(72) Inventor: **Hyo Sun Jung**, Incheon (KR)

(73) Assignee: **YONWOO CO., LTD.**, Incheon (KR)

(**) Term: **15 Years**

(21) Appl. No.: **29/942,570**

(22) Filed: **May 16, 2024**

(30) **Foreign Application Priority Data**

Dec. 4, 2023 (KR) 30-2023-0048984

(51) **LOC (15) Cl.** **09-05**

CLAIM

The ornamental design for a container for packaging, as shown and described.

DESCRIPTION

FIG. 1 is a perspective view of a container for packaging, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings show portions of the container for packaging that form no part of the claimed design.

1 Claim, 6 Drawing Sheets
